UNITED STATES PATENT OFFICE.

HERMAN E. S. CHAYES, OF NEW YORK, N. Y.

GRINDING-MACHINE.

1,265,050.

Specification of Letters Patent. Patented May 7, 1918.

Application filed August 16, 1915. Serial No. 45,750.

To all whom it may concern:

Be it known that I, HERMAN E. S. CHAYES, a citizen of the United States, residing at the borough of Manhattan, in the county of New York, city and State of New York, have invented certain new and useful Improvements in Grinding-Machines, of which the following is a specification.

My invention relates to grinding machines, more particularly to that class of machines known as "wet grinders," and its novelty lies in the construction and adaptation of its parts.

In the embodiment hereinafter described I have designed a machine that is self-contained, the unit of power being part of the device and the abrasive element being mounted on the power shaft of this unit, with special devices for quickly changing the abrasive element.

Further I have provided means for wetting and cleaning the abrasive element continuously during the operation of grinding, from a reservoir of water, and means for catching the splash and drip of the water and returning it to the reservoir. Means for dressing the abrasive element is also provided and the entire grinding device is inclosed within a casing of neat appearance.

Referring to the drawing, Figure 1 is a top plan view of the grinding machine, some of the parts being broken away and some shown in section. Fig. 2 is a vertical longitudinal section taken on the line 2—2 of Fig. 1, looking in the direction of the arrows. Fig. 3 is a vertical transverse section taken on the line 3—3 of Fig. 2, looking in the direction of the arrows, and Fig. 4 is a detail plan view partly in section of the dressing device.

The entire device is mounted on a base 1. The unit of power may be a motor 2 of any suitable size and design, and having a casing 3 and a drive shaft 4. On the end of the drive shaft 4 there is mounted a collar 5 the end of which is flush with the end of the shaft 4. To the end of the shaft 4 there is secured by means of a screw 6 a pulley 7 having a reduced end 8 thereby forming a shoulder 9. An abrasive element or stone 10 which may be of carborundum or like material and circular in shape is mounted on the reduced end 8 and is held securely clamped between the shoulder 9 of the pulley and the end of the collar 5 by the screw 6. Thus

when the shaft 4 revolves the stone 10 is also caused to revolve.

The devices for wetting, cleaning and facing the stone 10 are mounted and inclosed within a casing 21 which is oblong in shape while the two ends and top are semi-circular in cross-section. It is divided into two parts, a main case 21 and a cover 30. The main case 21 has a reversely inclined end 22 apertured at the top as at 23 and at the bottom as at 24. It is provided with lugs or feet 25 one on each side which are slotted as at 26 to engage the heads of screws 27, which secure the main case 21 to the base 1 and at the same time provide an adjustment of the case with respect to the center of the motor-shaft 4.

The cover 30 is adapted to rest on the top of the main case 21 and is held in position by lugs 31 integral with the inner sides and which project downwardly beyond its lower edge so as to engage the inner sides of the main case 21. This arrangement gives a perfect alinement of the cover with the case and at the same time gives a flush joint on the outside.

The cover 30 has an aperture 32 at the forward end, that is, the end nearest the operator or on the left as shown in Figs. 1 and 2, and this aperture registers and communicates with the aperture 23 in the case 21 when the cover 30 is in its proper position. At the forward end of the cover 30 on the side nearest the motor there is an aperture 33 through which the motor shaft 4 and the collar 5 project within the casing. An arc of the circular stone 10 projects out through the communicating apertures 23 and 32 in the case 21 and the cover 30 respectively.

At the bottom of the case 21 there is provided a reservoir 28 adapted to contain water for moistening the stone 10. The sides of the reservoir 28 are so shaped as to fit snugly within the case 21, while a spout 29 on one end thereof projects through the aperture 24 and beyond the front of the case 21.

In front of the casing 21 there is located a hand rest 11 which is preferably made of pressed glass or other material, which may be easily cleaned. The end of the rest 11 nearer the case 21 is bifurcated as at 12—12, forming a semi-circular recess adapted to fit close against the reversely inclined end 22.

22 of the main case 21. The under side of the rest 11 is hollowed out as at 14 and into this hollow the spout 29 of the reservoir 28 projects in such position as to be directly under the lower end of an inclined channel 16 located on the upper surface of the hand rest 11 and the central axis of which is in line with the central axis of the casing 21 and the grind-stone 10.

- 10 The upper surfaces 15—15 of the rest 11 on each side of the channel 16 are so molded as to readily fit the hands of the operator when in the position of holding an object against the revolving stone. Any water 15 dripping from the object or the fingers of the operator falls into the inclined channel 16, from which it runs into the spout 29 of the reservoir 28.

Means for conveying water from the reservoir 28 to the grind-stone 10 and cleaning the same, will now be described. A knob 34 is molded or otherwise secured to one end of a shaft 35, the other end of which is threaded at 36 and terminates in 25 a reduced portion or small knob 37.

The shaft 35 is adapted to support a stationary bracket 50 and a swivel bracket 40, the latter being shaped in the form of an arm 41 extending from a circular boss or hub 42 one side of which is reduced in diameter to form a boss 44. An undercut finger 43 protrudes from the side of the arm 41 adjacent to the junction of the arm 41 and the boss 42. Near the end of the arm 35 41 there is mounted a pulley 45 which is supported by a screw 46 the end of which is threaded into the arm 41.

The stationary bracket 50 is in the form of a bell crank having arms 51 and 52 and 40 a spool-shaped hub 53 having circular flanges 54 and 55 formed at each end, the latter having a notch 56 in its periphery. The arm 51 has a pin 56' near its end which extends horizontally from one side of the 45 arm, while at the end of the arm 51 there is mounted a screw 57 which is threaded into the arm 51 and provides a support for a large drive pulley 58 and a smaller pulley 59, which are preferably of one piece of metal.

The other arm 52 of the bell crank 50 has a slot 60 in its end and in which there is pivoted on a screw 61 a lever arm 62 having a toe 63 on one end and a roller 64 mounted 55 on a screw 65 threaded into the other end. A flat spring 66 secured to the arm 52 presses against the toe 63. The screw 61 also furnishes a support for a pulley 67, and the arm 52 also carries a roller 68 mounted 60 on a screw 69 which is threaded into the arm 52. An endless belt 70 is mounted on the pulleys 67, 59 and 45 and between the rollers 64 and 68, and it is preferably of elastic material. It has secured to it a block 65 of sponge rubber 71 which is adapted to

pass over the pulley 67 and through the water in the reservoir 28, then between the spring-pressed roller 64 and the roller 68 where the superfluous water is pressed out, thence over the pulleys 59 and 45 and passing 70 downwardly and against the periphery of the grind stone 10, which is moving in the opposite direction, it again enters the water where the waste of the grinding is washed out of the sponge 71. A belt 72 75 transmits the power from the pulley 7 to the pulley 58.

From the foregoing description of the construction of the brackets 40 and 50 it is obvious that I have a support for the moving parts that is easy and cheap to manufacture and being in two parts easy to assemble, yet when it is assembled gives all the advantages of one piece construction.

To assemble the brackets 40 and 50 within 85 the main case 21 the procedure is as follows: The swivel bracket 40 is placed against the bracket 50 so that the arm 41 is at right angles to the position shown in Fig. 2, the undercut finger 43 being in line 90 with the notch 56 in the flange 55. The finger 43 is passed through the notch 56 so that the undercut portion overlies the flange 55 on the bracket 50. The boss 44 on the bracket 40 then slips into a corresponding 95 recess in the bracket 50. The belt 70 is then passed over the pulleys 67, 45 and 59 and between the rollers 64 and 68; then the arm 41 is given a quarter turn with the finger 43 overlying the flange 55. The parts are 100 then placed within the case 21 so that the pin 56 on the stationary bracket 50 protrudes through the hole 19 in the side wall of the case 21.

The shaft 35 is now passed through the 105 hole 17 in one side of the case 21, then through a central bore in the hub 53 and into a threaded bore in the center of the hub 42 of the bracket 40. The reduced end or knob 37 on the end of the shaft 35 then 110 protrudes through a hole 18 in the opposite wall of the case 21. By turning the knob 34 the threaded end 36 of the shaft 35 screws into the bracket 40 thus binding the two brackets 40 and 50 together and at the 115 same time the knob 34 pressing against the side of the case binds the case between the knob and the flange 54 on the hub 53.

Means for dressing the stone 10 is provided for by mounting a shaft 72 in suitable 120 bearings in the side walls of the case 21. The shaft extends outside of one of the walls and is bent to form a lever handle 73. Within the case 21 and on the shaft 72 there is mounted a holder 74 having a forked end 125 75, the holder being secured to the shaft 72 by a set screw 76. A plurality of toothed wheels 77 are mounted on a screw 78 between the forked ends 75; they are adapted to revolve when brought in contact with 130

the stone 10. Normally the "dressers" hang down out of the way but when it is necessary to clean or dress up the stone 10 the handle 73 is rocked so as to bring the dressing wheels 77 up into a position indicated by the dotted lines in Fig. 2, where they press against the revolving stone and remove any uneven surface therefrom.

The center of the grind-stone 10 being 10 above the top of the main case 21 makes the screw 6 quite accessible when the cover 30 of the case is removed thus making it very easy to remove or replace the grind-stone.

15 Inasmuch as many changes could be made in the above construction, and many apparently widely different embodiments of my invention could be made without departing from the scope thereof, it is intended 20 that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, 3 might be said to fall therebetween.

I claim:

1. A device of the kind described, including a grinding wheel, an endless conveyer having a moistener attached thereto and co-operating with said wheel to moisten it, and means for expressing moisture from said moistener.

2. A device of the kind described, including a grinding wheel, an endless conveyer having a moistener attached thereto and co-operating with said wheel to moisten it and means for regulating the amount of moisture carried by the moistener.

3. A device of the kind described, including a grinding wheel, an endless conveyer having a moistener attached thereto and co-operating with said wheel to moisten it and means for removing the excessive amount of moisture carried by the moistener.

4. A device of the kind described, including a grinding wheel, an endless conveyer having a compressible moistening member attached thereto and co-operating with said wheel to moisten it and means for compressing the moistening member for expressing excessive moisture therefrom.

5. A device of the kind described, including a grinding wheel, an endless conveyer

having a moistener attached thereto and co-operating with said wheel to moisten it and 60 rollers between which the endless belt is arranged to pass for expressing moisture from said moistener carried thereby.

6. A device of the kind described, including a grinding wheel, an endless conveyer 65 having a moistener attached thereto and co-operating with said wheel to moisten it and spring pressed rollers between which the endless belt is arranged to pass for expressing moisture from said moistener carried 70 thereby.

7. A device of the kind described, including a grinding wheel, a liquid reservoir and means associated with said grinding wheel and the reservoir to moisten the said grinding wheel in combination with an arm rest 75 so associated with both the wheel and the reservoir to direct the drippings from said wheel back to the reservoir.

8. A device of the kind described, including a grinding wheel, a liquid reservoir and means associated with the grinding wheel and the reservoir to moisten the said grinding wheel, in combination with an arm rest having a groove therein and arranged adjacent the said wheel to direct the drippings 85 therefrom back to the reservoir.

9. A device of the kind described, including a grinding wheel, and a moistening element comprising a triangular frame having 90 rollers at each point thereof an endless belt mounted upon said rollers and a moistener attached to said belt and co-operating with said grinding wheel to moisten it.

10. A device of the kind described, including a grinding wheel, and a moistening element comprising a knock-down triangular frame having rollers at each point thereof of an endless belt mounted upon said rollers and a moistener attached to said belt and co-operating with said grinding wheel to 100 moisten it.

11. A device of the kind described, including a grinding wheel and a moistening element comprising a separable frame structure, rollers arranged on said frame over which an endless belt is adapted to pass and moistening members carried by said belt and co-operating with said grinding wheel to 105 moisten the same.

In testimony whereof I affix my signature in presence of two witnesses.

HERMAN E. S. CHAYES.
